F. H. HARDY,
ROTATABLE CYLINDER,
APPLICATION FILED JAN. 19, 1918.

1,281,777.

Patented Oct. 15, 1918.

Inventor:
Frank H. Hardy
by his attorney
Charles D. Richardson

UNITED STATES PATENT OFFICE.

FRANK H. HARDY, OF ANDOVER, MASSACHUSETTS.

ROTATABLE CYLINDER.

1,281,777.

Specification of Letters Patent. Patented Oct. 15, 1918.

Application filed January 19, 1918. Serial No. 212,777.

To all whom it may concern:

Be it known that I, FRANK H. HARDY, a citizen of the United States, residing at Andover, in the county of Middlesex and State of Massachusetts, have invented certain new and useful Improvements in Rotatable Cylinders, of which the following is a specification, reference being had thereto in the accompanying drawings.

10 My invention relates to means for securely fixing a journal at each end of a cylinder; but it is particularly concerned with what are known as "furnisher brushes" which are cylindrical, and are used to supply liquid dye to print-cloth rolls.

Heretofore these brushes have been tufted with bunches of bristles or fiber, by machinery, but it has been impossible to provide the long and hollow cylindrical wooden roll, with a journal at each end that could be successfully used for any reasonable length of time. The best method known has been to use two separate journals, each having a circular plate set into a circular seat 25 in the end of the cylinder, and there secured by long screws passing through holes in the plate, longitudinally into the end portion of the cylinder; but it was found that the screws soon worked loose, and the necessarily frequent readjustment of plates and screws in the ends of the cylinder, not only destroyed the ends of the cylinder, but rendered brushes, so constructed, unsalable to possible users.

30 Now by means of my invention the journal members may be secured to the end portions of the cylinder, without the use of screws or bolts of any kind; in fact they are secured from the inside of the cylinder 40 rather than from the outside.

These journals can be used over and over again with new brushes. They may be removed from a brush with great ease and speed; and may be as readily assembled, for example, with a new brush; all with a resulting saving of labor, and cost of material; and still further, they are cheaper to manufacture; and because of them, a machine-made brush, otherwise a failure 45 cause of faulty means for securing them to the cylinder, is made one of great value, especially as the resulting complete brush is cheaper to make.

In the drawing illustrating the principle 55 of my invention and the best mode now

known to me of embodying the same in operative structure,

Figure 1 is an elevation of a cylinder brush provided with my invention.

Fig. 2 is a longitudinal section of the same, enlarged and broken away to show the coöperating parts.

Fig. 3 shows in perspective one journal member, and binding rod; while

Fig. 4 illustrates in perspective, the various parts, in alinement, and ready to be moved toward each other, and secured together in operative position.

In the present embodiment of my invention I provide a wooden cylinder 1, preferably made of rock maple. It is turned to size, bored centrally and recessed in its opposite ends, in a manner that will appear clearly, later. Radial holes 2 are bored in the surface of the cylinder, for the reception 75 of tufts of bristles 3; after which, by a suitable brush-drawing machine, the tufts are inserted into the holes and there secured by wire staples 4.

A driving journal member 5 to be mounted in one of the recesses in the roll, is circular in cross-section, and consists of a journal 6, a flange 7 and collar 8 with inwardly extending bosses 9. In the longitudinal axis of the collar, is a slightly tapered threaded 80 hole for the reception of a correspondingly threaded binding rod 11, as a piece of gas pipe; while the opposite end 12 of the binding rod is similarly threaded to engage a second journal member 13, like the driving journal member 5, with a flange 14 and a collar 15, but no bosses, and having no provision to receive a pulley. The diameter of the collar of each journal member is the same as that of the longitudinal hole 16 through the cylinder, whose end portions are so recessed 95 see Figs. 2, 3 and 4, as to conform to, and be a counter-part of, the respective adjacent shapes of the collar, bosses and flanges found in the driving journal member and the second journal member, and being of such depth that the outside face of each flange is flush with the end face of the cylindrical wooden brush roll.

Now to assemble the various parts of my invention, the driving journal member 5 and the binding rod 11 are removably secured together, and the rod pushed through the longitudinal hole 16 in the cylinder, until the flange, bosses and collar have all found 110

their seats in the adjacent recess; after which time, the second journal member 13 is screwed onto the free end threaded portion 12 of the binding rod at the opposite end of 5 the cylinder, until the collar and flange find their seats in the hole and the recess in the adjacent end of the cylinder. By giving a hard turn to the second journal member 13, as by means of a wrench, the two journal 10 members and the wooden cylindrical roll may become absolutely rigidly bound together, longitudinally and rotatively; and for all practical purposes become a unitary structure, with no opportunity for the liquid 15 dyes, furnished by the roll, to affect in any way the mechanical means for securing the journals to the roll, as would be the case, were there screw holes in the flange, through which the liquid dye could pass, and begin 20 to rot the wood around the flange screws.

In short, I have provided a roll of any length with demountable end journals, all bound rigidly together by mechanical means, located entirely within the roll, and

protected from injurious influences outside 25 of the roll.

Desiring to protect my invention in the broadest manner legally possible,

What I claim is:—

A cylinder with a longitudinal hole there- 30 through; two separate journal members each having a circular collar thereon fitting into the two end portions of said hole; a boss connected with one of said collars, and a corresponding recess cut in the end portion 35 of said cylinder for the reception of said boss, to bind the cylinder and the journal together rotatively; a binding rod, of a diameter smaller than that of the said hole in the cylinder, and provided with threaded means 40 to engage corresponding threaded means in the two collars, to bind the two journal members and cylinder together, longitudinally.

In testimony whereof I hereunto affix my 45 signature.

FRANK H. HARDY.
